TELEVISION RECEIVING AND PROJECTING
MEANS AND METHODLee de Forest, Hollywood, Calif., assignor to
American Television Laboratories, Inc., a cor-
poration of Delaware

Application September 22, 1931, Serial No. 564,331

6 Claims. (Cl. 178—5)

This invention has to do in a general way with the art of forming pattern pictures or reproducing images in an opaque coating on a transparent or diaphanous base material such as film or the like.

More specifically, the invention has to do with improvements in the invention disclosed in my copending application Serial No. 532,454, filed April 24, 1931, in that it contemplates a novel type of film and the method of producing and using same for effecting the results contemplated in my former application.

My former application has to do with television receiving apparatus and discloses means for reproducing and projecting received televised images. As pointed out above, the present invention relates to improvements in apparatus of this character, and while the invention is described in connection with television receiving apparatus, it is to be understood that the invention is not necessarily confined to apparatus of this character, but may find various other applications in the reproduction of images to form pictures or in the formation of various designs and patterns.

The method described in my former application has to do with the formation of images upon a film or suitable base member by electrically etching an opaque coating on the base member. The type of film described therein consisted of ordinary motion picture film which had been uniformly exposed and developed to leave a deposit of silver in the gelatine on the so-called emulsion side of the film. The film treated in this manner was then passed between a stationary conducting plate and a revolving disk, the latter having provided upon its periphery a plurality of equally spaced discharge points. The discharge points of the disk and the stationary plate were connected to a source of high frequency oscillating electrical energy which was modulated by received television signals coming from a television receiver. The disk was rotated at a very high rate of speed, corresponding to the speed of a scanning disk at the television transmitter so that the film in passing thereunder was subjected to the action of electrical discharge from each point, the discharge corresponding in intensity to the light impressing the photoelectric cell at the transmitter, such light being received from the object or image being televised in any well known manner. Because of the high rate of speed of the moving discharge there is practically no danger of igniting the film or base since the

discharge does not remain adjacent a given area of the film for a sufficient length of time to raise the temperature thereof appreciably.

In using the method and apparatus as disclosed in my co-pending application, I have found that the presence of an emulsion or gelatine in connection with the silver deposit on the coated surface of the film deters to a certain extent the etching or engraving action of the electrical discharge, thus impairing the sharpness of the image and having a deleterious effect upon the tone qualities of the finished picture. I have, therefore, conceived and developed a novel type of film which is particularly adapted to this use in that the coating which is subjected to the action of the spark or discharge comprises a thin uniformly distributed layer of pure metal. The thickness of this layer is preferably of the order of several wave lengths of yellow light.

In using film of this nature with apparatus of the type disclosed in my former application, I consider it preferable to employ a wiping brush or roller which forms a direct contact with the metallized surface of the film. This brush or roller is connected to the energized circuit which has a discharge point situated above the region of the film to be etched or engraved. This feature has one advantage over the apparatus shown in my former application in that the circuit across the discharge gap is completed without necessitating the discharge to take place through the film base.

The details in the construction of a preferred form of apparatus used in etching or engraving film, together with a preferred process of coating the film, will be best understood from the following description of the accompanying drawing which is chosen for illustrative purposes only, and in which:

Fig. 1 is a plan view showing a preferred form of film coated in the manner contemplated by this invention;

Fig. 2 is a plan view of the film etching or engraving apparatus illustrating the manner in which a film is passed therethrough;

Fig. 3 is an enlarged sectional view which may be considered as having been taken along the line 3—3 in Fig. 2; and

Fig. 4 is an enlarged section showing the details in the construction of a preferred form of discharge gap.

Referring to the drawing, I have shown in Fig. 1 a section of film 11 which is of the type ordinarily used in connection with motion pictures in that the edges of the film are provided with per-

forations 12 adapted to be engaged by suitable sprocket wheels such as are employed in the usual type of projecting apparatus. In this particular film the central portion between the perforations 12 is provided with a thin coating as indicated by reference numeral 13. This coating may be comprised of any suitable metal which can be uniformly applied, such as silver, magnesium, gold, and the like, and as pointed out in the fore part 10 of the specification, is of the order of several wave lengths of yellow light in thickness. For my purpose the film 11 may be of any suitable transparent or diaphanous base material such as clear, uncoated celluloid film.

15 Although film of this character may be coated in long lengths by various processes, I consider it preferable to coat the film by first cleaning the same in lye to remove all grease, then washing the film with tap water, thereafter scrubbing the surface of the film with a rotating scrubbing brush, after which it is passed through a bath of stannous chloride. The next step is to wash the film in tap water, followed by a thorough washing in distilled water, after which the film is passed 20 through a silvering bath which may be of any one of several suitable solutions for depositing silver on organic surfaces. The silver deposited on the film by this first bath is extremely thin and the film is then washed in distilled water and may be 25 passed through a second silvering bath similar to the first which materially increases the thickness of the silver deposit on the film. Although most of the silver has so far been deposited on the cleaned surface of the film, it is important to remove any silver which has deposited on the opposite or celluloid side. For this purpose I pass the film again through a lye bath and over a scraper which removes any silver which may have been deposited on the reverse side of the film. This 30 side of the film is then scrubbed by passing over a rotating scrubbing brush and is given a final washing in tap water. For this final washing step the film is passed directly through a dryer where it passes over a number of rolls in a chamber 35 through which hot, dry air is circulating. When the film emerges from the drying cabinet it is rolled on reels holding 400 to 1000 feet, as the case may be, and is then ready to be used in the etching or engraving apparatus which will herein- 40 after be more fully described.

It is sometimes preferable to protect the newly applied metallic surface by applying a thin layer of transparent varnish or lacquer or a thin layer of amyl acetate thereto. Inasmuch as it is highly important to make as perfect a contact as possible between the metalized surface and the point of contact in the electrical etching apparatus, I prefer to limit the area of metalized surface thus protected (when the entire surface of 50 the film is coated with metal) to the area indicated at 13 in Fig. 1. In this manner the perforated margins of the film are provided with the metal coating but are not insulated in any way by the varnish or lacquer so that rollers or wiping brushes can make good contact with these uninsulated margins. If, on the other hand, I do not choose to coat the metalized surface with a varnish, as pointed out above, I prefer to limit the coated area to the portion indicated at 13. 55

60 The object of so doing is to sharply limit the sparking action of the traveling discharge points to the area of film directly between the perforations. In producing a film with uncoated margins, as shown in the drawing, I may either coat the two margins with paraffin, molten

wax, or the like, before the film passes through the silvering solution, or I may dip the margins of the silvered film in a dilute solution of nitric acid. Various other means for producing film with uncoated margins will no doubt appear to 5 those familiar with the art.

In Figs. 2 and 3 I show a preferred form of apparatus which may be used in etching or engraving film of the type described above. This apparatus consists in a general way of a disk 10 or rotatable plate 15 which is secured to a bearing hub 16 mounted upon a shaft 17. The disk is provided near its periphery with a plurality of equally spaced discharge points 18 which may be of the type shown and described in my co-pending application, or may be constructed as shown in Fig. 4 which will be described later in the specification, and each of these points is connected through an insulated conductor 19 to a segment 20 of a commutator 21. The commutator 21 has wiping contact with a brush 22 which is connected through a conductor 23 to a suitable source of electrical energy, not shown. The film 11 passes over a stationary plate or bridge 24 so that its coated surface is in close 25 proximity to the path traversed by the discharge points 18. The coated surface of this film is engaged by a wiping brush or conducting roller 21 mounted between suitable resiliently controlled arms 28 and having electrical connection with a 30 conductor 29 which is also connected to the source of electrical energy.

As pointed out in the fore part of the specification, the energy delivered to the contact roller 27 and the successive discharge points, is of a 35 high frequency oscillating type in which the oscillations are modulated so as to vary the intensity of the electrical discharge. In the form of apparatus shown in my co-pending application which is used for reproducing televised images, 40 modulations referred to are obtained from a television receiving circuit of any standard type so that each discharge point as it rapidly swings transversely across the more slowly moving film is effective to perforate the film coating along a 45 transverse line. This line, when viewed under the microscope, is shown to be made up of a very large number of fine, individual perforations. The size of these perforations and the separation between the same depends upon the amount 50 of electrical energy in the discharge between the point and the metalized surface, the distance of separation, the velocity of the moving part, and the condition of the air (temperature, degree of ionization, etc.) in which the discharge takes 55 place. It will be seen, therefore, that when the disk 15 has the same number of discharge points as the scanning disk of the television transmitter has perforations, and is rotating in synchronism with the scanning disk at the television 60 transmitter, the intensity of the discharge of each point, as its corresponding commutator is engaged by the brush 22, will vary directly with the intensity of the light passing at that instant through the corresponding aperture in the scanning disk. In this manner the line traced by the discharge point varies in opacity with a corresponding line on the object or image which is "viewed" by the photoelectric cell associated 65 with the transmitter scanning disk. Thus I am able to produce half tone pictures of the image at the transmitting station in rapid succession and when such pictures are produced on the motion picture film as shown, they may be im- 75

mediately projected through a projecting apparatus of the type shown in my co-pending application.

For the purpose of immediately removing from the spark gap all of the fine metal dust which is released thereby, I may provide a blower 30 which is provided with a nozzle 31 positioned so as to direct a stream of air into the spark gap immediately above the film.

10 In Fig. 4 I show a preferred form of discharge point 18 which embodies a thick walled capillary tube of glass or other insulating material indicated at 35 mounted in the disk 15 with its lower end at a distance of from .001 inch to .003 inch 15 above the coated surface of the film 11. The passage 36 through the capillary contains a conductor 37 which is cemented or otherwise secured therein with its lowermost end spaced above the lower end of the tube as shown. The distance 20 between the lower end of the conductor 37 and the bottom of the capillary may be varied over quite a wide range. I have obtained very good results with the lower end of the conductor spaced from .003 inch to .007 inch above the lower end 25 of the capillary. In practice I have found that a discharge point of this nature produces a fine brush like discharge or spark which traces a fine line across the coated surface of the film, the line varying in density with the modulations in 30 the current.

The pure metal coating, as described above, may be applied directly to the surface of an uncoated celluloid film or it may be applied upon a surface which has previously been coated with 35 emulsion. It is an important feature, however, that the silver is not applied in conjunction with an emulsion or gelatine, but is in the nature of a pure metal surface which is extremely thin and is uniformly distributed.

40 It is to be understood that while I have described in the fore part of my specification a preferred method of applying this coating, other methods may be employed without changing the effectiveness of the process. For example, instead of using a method of chemical deposition as described above, I may deposit the metal on the surface of the film in a vacuum by one of the well known sputter or cathodic deposition methods. In this case the entire process of coating the film takes place in a large chamber which 45 is continuously exhausted of air to the desired degree of vacuum and the film to be coated is slowly rolled from one spool to another by means of suitable power mechanism and reduction gearing, all of which is preferably contained within 50 the evacuated chamber. In passing between the two spools the film is drawn in close proximity to an electrically heated wire or ribbon composed of the metal (such as magnesium) to be deposited thereon. During this process extremely minute 55 metallic particles are released or vaporized from the metal by the combined action of the heat

and electrical repulsion in the vacuum and are deposited in a thin even layer upon that portion of the film which is passing adjacent to the disintegrating metallic body. In this case, as in the chemical deposition process, the thickness of the deposited metal layer can be gauged by controlling the speed at which the film is passed through the metalizing bath or solution. In the chemical process described above I prefer to pass the film through the bath and dryer at slow speed, preferably at from one to two feet per minute.

5 It is to be understood that while I have herein described certain preferred methods of treating or coating the film and have illustrated and described one preferred form of apparatus which 15 may be used in etching or engraving the film, the invention is not limited to the precise details in these descriptions, but includes within its scope whatever changes fairly come within the spirit of the appended claims.

20 I claim as my invention:

25 1. For use in making television pictures, a transparent film having a continuous coating of substantially pure metallic silver applied to one surface thereof.

2. For use in apparatus for electrically etching a coated film: a rotatable disk; a plurality of angularly spaced capillary tubes mounted transversely in the periphery of said disk; a discharge conductor mounted in the passage through each 30 of said tubes; a segmental commutator on said disk; conductors connecting each discharge conductor with one of the segments in said commutator; means for supporting a film below said disk; and means for connecting each segment 35 with a source of potential as it traverses a film, said discharge conductors terminating above the lower ends of said capillary tubes.

3. In an apparatus of the class described, means for etching a normally transparent film 40 comprising a source of high frequency current having modulations corresponding to the etchings to be produced on said film, a rotatable capillary electrode carrier, said electrode terminating above the lower end of said capillary, means for applying said modulated currents to said coating and 45 said electrode, and means for rotating said carrier and for moving said film in timed relation thereto.

4. For use in making television pictures, a 50 transparent film having a continuous coating of substantially pure metal applied to the entire area of one surface thereof.

5. A moving picture film having a continuous coating of substantially pure metal applied to the 55 entire area of one surface thereof.

6. A moving picture film having a continuous coating of substantially pure metal applied to the entire area of one surface thereof and a continuous coating of varnish over a central portion of 60 said metallic coating.

LEE DE FOREST.
